STEEL CENTERING

August K. Wetzig, Beaver Falls, Pa., assignor to
 Koppel Industrial Car and Equipment Company,
 Koppel, Pa., a corporation of Pennsylvania

Application December 5, 1935, Serial No. 53,028

3 Claims. (Cl. 25—131.6)

The invention pertains to steel centering or forms used in the erection of concrete structures and more specifically to forms used in the construction of concrete sewers and tunnels. The forms are mounted upon a carrier for the purpose of moving the form to successive positions in casting the sewer and the invention lies in the means connected to the forms and carrier for the purpose of manipulating the forms into collapsed or expanded position.

Steel centering of the type disclosed and claimed in the appended specification and drawings is of the general type disclosed in Patents 2,020,519 and 2,020,520 granted November 12, 1935 to L. J. Sarosdy, and differs specifically therefrom by the specific embodiment disclosed in the drawings of the present application for manipulating the steel forms about the carrier.

An object of the present invention is to provide a novel and efficient means for supporting, collapsing and expanding a steel form upon a carrier, which means requires the services of but one man to manipulate the respective devices disposed on opposite sides of the carrier.

Another object of the invention is to provide a means for supporting, expanding and collapsing a form about a carrier which means may be readily detachable from the form and the carrier, and attached to another form for collapsing the same and moving to a new position.

A further object of the invention is to provide a means of the character described for supporting, expanding and collapsing the form about a carrier, which means may be adjustable within certain limits so as to move the form bodily laterally of the carrier and to be adjustable so as to be used with forms of varying dimensions.

Referring to the drawings forming a part of this specification, Fig. 1 is a transverse section through a concrete sewer showing the form in expanded position ready for the pouring of the concrete; Fig. 2 is a similar view showing the form in collapsed position after the concrete has set; Fig. 3 is a section taken on the lines 3—3 of Fig. 1 showing the connection between the lower arms of the form support and the carrier.

Although only a transverse section of the form has been shown, it will be understood that the forms may be constructed in any desired contour and length, depending upon the requirements of the specific structure being erected. Only conventional designs of form and carrier have been shown and described, but it will be understood that the form and carrier may be of any suitable length for the purpose in which they are to be

used. The manipulating devices as hereinafter described are connected between each side of the carrier and form and may be of any desired number. Obviously, in order to maintain the forms in equilibrium upon the carrier there will be required at least two of such devices mounted in longitudinal spaced relation on the carrier and as many additional devices as may be necessary to support the weight of the forms.

Referring now to Fig. 1 of the drawings showing the form in position for pouring the concrete, reference character 1 indicates a previously poured invert having rails 2 disposed longitudinally thereof and a carrier 3 mounted on the rails by means of wheels 4 secured beneath the carrier. At each side of the carrier are vertically disposed carrier members 5 upon which are mounted the form supports hereinafter described. It will be understood that the number of members 5 depends upon the number of supporting and manipulating devices used and the strength of carrier required. The steel centering or forms may be of any desirable contour and construction. In the drawings they are shown as comprising a skin plate 6 suitably braced by ribs 7 and hinged at the top on the longitudinal center line by means of hinges 8 secured to the members 7. A diagonal brace 9 is connected to each side wall and the adjacent ceiling portion of the form to further strengthen the form.

For the purpose of supporting the form upon the carrier and manipulating the two halves of the form, a device is connected between each side of the carrier and the adjacent portion of the wall form, which device comprises a member 10 pivotally connected at its inner end to the carrier as by the member 11 of the carrier by means of pin 12 and pivotally connected at its outer end to a member 13 of the form by means of the pin 14. It will be obvious from an inspection of the drawings that the members 10 may be directly connected to the members 5 of the carrier or any other suitable portion of the carrier. For the purpose of adjustment the member 10 has incorporated therein a turnbuckle 15. The members 10 of Fig. 1 are shown as tension members, taking the vertical component of the weight of the form. Disposed transversely of the carrier beneath the members 10 and having its opposite end portions secured to the form members 13 is a member 16 comprising a ratchet jack 17 disposed between the members 5 of the carrier and having collars 18 engaging the carrier members 5 so as to retain the barrel 17a of the ratchet jack 17 in fixed relation transversely of the carrier and permit rela-

tive vertical movement between the ratchet jack barrel 17^a and the carrier members 5. The relation of the ratchet jack to the carrier members 5 is better shown in Fig. 3 in which the spaced carrier members 5 are shown engaged by the collar 18. The opposite end portions of the ratchet jack 17 are connected to the form members 13 by means of the pins 19.

It will be obvious to anyone skilled in the art that the pins 14 and 19 may be made removable to provide for the ready detachment of the arms 10 and 16 from the form and likewise that the pins 14 and 19 may be separated a greater or lesser distance than shown in the drawings, or the pins 14 and 19 may be combined by forming one of the members 10 or 16 with end portions in the form of a clevis and fitting the end of the other member into the clevis and securing both the clevis and member to the member 13 of the form by means of a single pin. Such a connection is shown in Sarosdy Patent 2,020,519 referred to supra.

Assuming the form to be in the expanded position as shown by Fig. 1 of the drawings and it is desired to collapse the form into the position shown by Fig. 2 of the drawings, the wedge bracing 20 and lateral bracing 21 are first removed to permit the collapsing of the form. The operator then grasps the handle of each jack 17 and manipulates the handle to retract the end portions of the member 16 within the barrel 17^a. During this collapsing or shortening movement of the member 16, the form is suspended upon the carrier by the members 10 which rotate downwardly toward the carrier simultaneously with the shortening of the member 16, and the ratchet jack barrel 17^a slides downwardly between the members 5 of the carrier. Due to the hinging of each half of the form by means of the hinges 8, the lower ends of the form move inwardly and the whole form moves downward and inward, away from the concrete. The result of such movement is to bring the form into the position shown by Fig. 2 of the drawings.

It will be obvious that with the form in the position as shown by Fig. 2, the carrier and form can be moved to a new position and by suitable manipulation of the ratchet jack 17 the form can be expanded into the position shown by Fig. 1 of the drawings and the bracing 20 and 21 be inserted so as to position the form for pouring another section of the sewer or tunnel.

Should it be necessary for any reason, to shift the form bodily laterally of the carrier, this may be readily accomplished by shortening the members 10 at one side of the carrier and correspondingly lengthening those members 10 on the opposite side of the carrier. In a like manner the threaded arms of the member 16 could be adjusted to compensate for changes in the arms 10.

An obvious modification of the invention, which it is believed not necessary to disclose in the drawings, may be obtained by reversing the members 10 and 16 so as to place the members 10 into com-

pression and use the device for manipulating the side walls of the form. Obviously, in such a construction it would be necessary to provide a separate support for the ceiling portion of the form should the form be provided with a ceiling portion. Such a ceiling support could obviously be the same as disclosed in Fig. 1 of the drawings.

It will likewise be obvious to those who are skilled in the art that various modifications may be made in the details of construction without departing from the scope of the invention as contained in the appended claims.

Having thus described the invention what I claim as new and desire to secure by Letters Patent is:

1. In combination, a carrier and a collapsible form, means supporting the form upon the carrier and comprising a plurality of members pivotally connected at each side of the carrier and to the adjacent side of the form, a member having individually adjustable oppositely disposed end portions pivotally connected to the form at each side of the carrier, an intermediate portion slidably mounted upon the carrier for vertical movement, and means incorporated in the said intermediate portion for actuating said end portions of the member to expand and collapse the form.

2. In a mold apparatus in combination, a rigid carrier, a collapsible form, means at each side of the carrier forming a support for the form and for expanding and collapsing the form about the carrier, each means including a member pivotally connected between the carrier and the adjacent side of the form, and a member common to said means on one side of the carrier and the means on the opposite side of the carrier, said common member having its opposite ends pivotally connected to the form, its intermediate portion slidably connected to the carrier for vertical movement only, and including a means for actuating the end portions of said common member to effect the expanding and collapsing of the form about the carrier.

3. In a mold apparatus in combination, a rigid carrier, a collapsible form, oppositely disposed means at each side of the carrier forming the support for the form and for expanding and collapsing the form about the carrier, each means including a member pivotally connected to the side of the carrier and to the adjacent side of the form, and a member common to said means on one side of the carrier and the means on the opposite side of the carrier, said common member having its opposite end portions connected to the side walls of the form, its intermediate portion slidably engaging the carrier and having bearings engaging the carrier to prevent relative lateral movement between said intermediate portion and the carrier, and means cooperating with said intermediate portion for moving the end portions of the common member laterally of the carrier and intermediate portion.

AUGUST K. WETZIG.
